35 INVENTOR
Joseph O. Cadieux
BY ATTORNEY

UNITED STATES PATENT OFFICE.

JOSEPH O. CADIEUX, OF MERIDEN, CONNECTICUT, ASSIGNOR TO THE CONNECTICUT TELEPHONE & ELECTRIC COMPANY, INCORPORATED.

SIGNAL DEVICE.

Application filed July 2, 1923. Serial No. 649,093.

To all whom it may concern:

Be it known that I, JOSEPH O. CADIEUX, a citizen of the United States of America, residing at Meriden, New Haven County, Connecticut, have invented a new and useful Signal Device, of which the following is a specification.

My invention relates to an electric circuit controlling device particularly for hospital signal systems and the like.

The main object of my invention is to provide a simple, reliable, and durable construction by which connection can be readily made and which is moisture proof.

Another object is to provide a construction of the multiple plug connecting type which will insure proper connection of multiple circuits.

Another object is to provide a construction of this character which is not only safe electrically but substantially unbreakable.

In carrying out the invention in its preferred form I have illustrated a push button call device cord with plug attachment.

Figure 1 is a perspective view of a construction embodying the improvements of my invention.

Fig. 2 is a cross sectional view of a wall plate or signal station with the plug in place.

Fig. 3 is a rear view of a multiple plug.

Fig. 4 is a longitudinal sectional view of the push button switch end of the device.

In the construction shown, the signal station has a face plate 5 which carries a frame consisting of two insulating members 6 and 7 connected by one or more studs or posts 8 which also secure the members 6 and 7 to the plate 5. The rear insulating plate 6 carries a plurality of spring contact fingers 9, in this instance four. The insulating plate 7 is seated in an opening in the face plate 5 and is itself provided with a plurality of openings corresponding in number and position to the contact fingers 9 which are the terminals of the signal circuits.

A plug device has an end plate 10 of insulating material carrying a plurality of pins or plug contacts 11 corresponding in number and position with the spring contacts 9. Each of these pins 11 is connected to a circuit terminal 12 secured to the back of the disk 10. The circuit terminals and disk 10 are surrounded by a metal casing

or shell consisting of the cylindrical body part 13 and the end cap 14 with one end of the body 13 spun over or flanged as at 15 to center and protect the disk 10. The cap 14 has a flange 16 snugly fitting the opposite end of the body 13 and secured to it in a suitable manner as for instance by one or more screws 17. The shell or casing is preferably lined with insulating fiber consisting of the disk 18 which is clamped in the bead of the cap 14 and secured by the eyelet 19 and the tubular portion 20 which fits between the disk 18 and the disk 10.

The cable containing the multiple conductors connected to the terminals 12 of the pins or plugs 11 is preferably protected by a yielding rubber tube 21 which provides a sanitary covering which is not only waterproof but substantially non-absorbent and therefore less likely to be contaminated than 75 a braided or woven covering. An annular ring 22 is preferably mounted on the end of the conductors inside the plug casing and held in place by the end of the cable covering which is stretched over it as shown in 80 Figure 2. This provides a tight joint on the cable at this point and also substantially seals the end of the cable within the casing. It also serves as a strain relief so that a pull on the cord or cable is taken up by 85 the thrust of the soft bulbous portion of the covering 21 at the end of the casing instead of by the connections of the wires with the terminals 12.

To insure the proper positioning of the 90 plug contacts I prefer to provide what may be termed a pilot pin 23 which is moulded or otherwise secured in the face disk 10 of the plug and adapted to loosely fit an opening 24 in the face of the wall plate. It will 95 thus be seen that it is possible to insert the plug in only one position. It is therefore impossible to make a wrong circuit connection with the plug with respect to the contact springs in the station.

To prevent the casing of the plug from turning with respect to the disk 10, I may provide a slot 25 in the edge of the disk to receive the lug or projection 26 which is indented from the outer edge of the shell 13.

The push button construction shown in Fig. 4 has a plurality of spring contact fingers such as 29 and 30 secured to an insulating base 31. The longitudinally movable contact member 32 is adapted to be 110

operated by a push button 33. This switch is mounted within a casing consisting of the body shell 34 and a cap member 35 suitably secured together for instance in the same 5 manner as the parts of the shell in Fig. 2. This casing is provided with an insulating lining consisting of the parts 36 and 37. The part 36 may be secured in place by an eyelet member 38 around the orifice in the 10 end of the casing in a manner similar to the securing of the disk 18 in the cap of the casing of Fig. 2. The end of the cable is anchored in this switch casing in a manner similar to the anchorage in the plug casing 15 in Fig. 2. Here the insulating ring 39 surrounds the ends of the wires adjacent the base 31 and the rubber covering of the cable is stretched over this ring to form a seal and strain relief as before described.

20 I claim:—

1. In a construction of the character described, a face plate, a frame secured to the rear thereof having two insulating members connected together, one of said insulating 25 members extending through said face plate, a plurality of contact springs carried by the other insulating member, the first mentioned insulating member having openings in line therewith and having another opening eccentric thereof and adapted to receive the 30 pilot pin of an attachment plug for properly positioning such plug.

2. A multiple attachment plug of the character described comprising a casing formed of two metal parts detachably connected together, an insulating disk arranged in one part and having a plurality of projecting contact pins, an insulating disk forming a lining for the other part, an 35 eyelet securing said disk to said other part and providing a cable passage and a tubular lining in said casing between said insulating disks.

3. A multiple attachment plug of the

character described comprising a metallic 45 casing consisting of a cylindrical part and a beaded cap having an opening for a conductor cable, an insulating disk secured within the bead of said cap, an insulating disk secured within the end of the cylindrical part of the casing, means for preventing rotation of said latter disk, a plurality of contact pins extending from said latter disk and an insulating lining interposed between 50 said disks.

4. In a device of the character described, a metallic casing formed of two detachably connected parts one of which has an opening therein, an insulating lining in said part surrounding said opening, an eyelet 55 securing said lining in said part, said eyelet forming a conductor passage, an insulating member secured within said casing, a plurality of circuit terminals secured to said insulating member opposite said eyelet, a 60 multiple conductor cord connected to said circuit terminals and extending through said eyelet, a soft rubber covering for said cord and means within said casing for spreading said rubber covering around the 65 inner edge of said eyelet.

5. In a device of the character described, a metal casing formed of two detachably connected parts, one of which has an opening therein, an insulating member secured 70 within the casing opposite said opening, circuit terminals carried by said insulating member, a cable connection extending through said opening into said casing and having wires connected to said terminals, a ring surrounding said wires within said 75 casing and a soft rubber covering for said cable extending through said opening and having its inner end spread over said ring and providing a yielding shoulder sealing 80 said opening.

JOSEPH O. CADIEUX.
